UNITED STATES PATENT OFFICE.

SAMUEL SUEKOFF, OF CHICAGO, ILLINOIS.

CUSHION-COVER CONSTRUCTION.

Application filed July 12, 1925. Serial No. 44,416.

To all whom it may concern:

Be it known that I, SAMUEL SUEKOFF, a citizen of the United States of America, and a resident of Chicago, in the county of Cook and State of Illinois, have invented a certain new and useful Improvement in Cushion-Cover Constructions, of which the following is a specification.

This invention relates to improvements 10 in spring cushion construction, and more particularly to an efficient and economical method of fabricating and assembling cushion covers adapted for use with resilient filling units such as springs or cushioning material.

As commonly made, a cushion cover consists of pieces of fabric usually burlap, cut and sewn together not only to form the bottom, top and side walls, but a series of individual cells or pockets within the outer walls and adapted to contain the resilient material units. The problem of making cushion covers is not merely one of structure, but it is one of method of preparing the material for 25 sewing, and then sewing the pieces together, so that the cushion can be loaded with resilient material with the least amount of time and labor.

The object of the present invention is, 30 therefore, to provide a method of further reducing the labor cost of cushion construction, attention being called to the fact that in the present highly competitive state of the cushion industry, an unprofitable business may become profitable by an apparently inconsequential saving in the item of labor costs. Thus, the elimination in one step of the manufacturing process, or the completion 35 of two steps in a single operation, or a more efficient treatment of the material in preparation for assembling, would be important to the manufacturer in meeting competition.

Of such a nature is the present invention 40 and its applicability to the art will be better appreciated as the process is disclosed with the aid of the accompanying drawings, in which—

Figure 1 is a perspective view showing a 45 portion of the material forming one of the covers, said material being marked off for subsequent sewing of partition strips along predetermined lines.

Figure 2 is a similar view of the piece

shown in Figure 1 but illustrating the arrangement of two sets of partition strips as applied thereto to form a base.

Figure 3 is a fragmentary view of a top cover with partition walls in place ready to be attached to the bottom piece shown in 60 Figure 2.

Figure 4 is a detail view in vertical section showing the top and bottom members partially joined together in the process of 65 assembling.

Figure 5 is a view similar to Figure 4 but taken at right angles thereto showing the method of joining some of the partition strips adjacent their centers in the assembling operation.

Figure 6 is a detail of a comb before sewing into the structure.

Regarding first the structure of the cushion as a whole, a portion of which is shown in Figures 4 and 5, the same consists of top 75 and bottom pieces 1 and 2 of suitable fabric such as burlap, sewn together at their edges in a seam 3 extending around the cushion between the top and bottom thereof, the marginal portions of these pieces forming a 80 boxing, or end and side walls of the cushion.

Within the outer covering formed by the pieces 1 and 2 are a series of continuous partition strips 4 extending the full length (or width) of the cushion with the longitudinal edges sewn to the top and bottom cover pieces. These partition strips are parallel with each other and divide the interior space of the cushion into a plurality of full length compartments.

In connection with the compartments formed between the partition strips 4 and between the outer of said strips and the parallel end (or side) walls of the covers are provided a plurality of division walls 5 95 which divide the cushion into a plurality of smaller compartments or cells. In the finally completed cushion, each of these division walls 5 is made up of two parts 5^a—5^a sewn together adjacent their center on a seam 100 5^b, as will hereinafter appear. Each set of tabs 5^a—5^a is made up in two sets of oppositely disposed strips or combs indicated generally by numerals 7 and 8, as shown separately in Figure 6, 105 the lower strips or combs 7 being attached to the bottom cover 2 as shown in Figure 2, while the upper strips or combs 8 are at

tached to the upper cover 1, as shown in Figure 3. The various steps taken in constructing the complete cushion cover will now be described.

5 The first step in the process is to provide a pair of similar top and bottom pieces 1 and 2 having sewing lines 10—10 arranged at right angles to each other, to outline the size of the compartments or cells of the complete cushion. To one of these pieces of material, as for instance the bottom piece 2 as shown in Figure 2, is secured a comb 7, shown in Figure 6. This comb is cut from a single piece having a series of notches or cuts 5^e formed therein and extending almost to the base 7^a to form tabs 5^a, this base being of sufficient width, however, to permit the comb to be secured to the cover 2 along a seam 12 which follows one set of the sewing lines 10 thereon. The arrangement is such that when thus secured to the base 2, the bottom margins of slots 5^e—5^e reach substantially to the bottom cover 2, as shown in Figure 2. An entire series of strips 7 are arranged in parallel relation along adjacent sewing lines 10—10 on the base 2 and thereafter a plurality of transversely disposed partition strips 4 are also secured to the cover 2 along seams 4^a, these seams following transverse sewing lines 10 and passing through the aligned notches 5^e—5^e as shown in Figure 2. As indicated in dotted lines in this figure, it will be seen the partition 4 is substantially twice as high or 35 wide as the combs 7.

Referring now to the top piece 1, a plurality of combs 8 of construction similar to combs 7 shown in Figure 6, are arranged along parallel seams 13 to correspond with 40 the similar combs 7 secured to the bottom cover 2. The arrangement is such that the top cover 1 with its combs 8 assembled thereon may be fitted over the bottom cover 2 with its combs 7 and partitions 4 in position to be secured together in finally 45 assembled form, as shown in Figures 4 and 5. The preferred method of securing these parts may be described as follows:

Starting along one edge of the cushion 50 parallel with the partition strips 4, the cells or compartments are completed progressively in rows toward the opposite edge of the cushion substantially as follows: The first row of tabs 5^a—5^a of the abutting 55 combs 7 and 8 between the first partition strip 4 and the cushion edge are sewn together along seams 5^b. The free upper edge of the first partition 4 is then inserted in corresponding notches 5^e and sewn to the 60 upper piece 1 along a seam 4^b, as shown in Figure 4, this sewing operation being continuous throughout the entire length of the partition 4 to complete the first row of compartments between the first partition 4 and 65 the adjacent end wall. The assembling op-

eration may then be continued as follows: The second row of pairs of abutting tabs 5^a—5^a adjacent the first partition strip 4 are joined along seams 5^b, and then the second partition strip 4 is sewn to the top 70 cover 1, to complete the second row of compartments. This operation is then repeated until all the compartments are formed. One or more of the side and end walls may be closed or boxed along seams 75 3 at any time in the process, although, of course, the cushion is not finally closed or boxed along all sides until the individual compartments are loaded with suitable resilient material, as will hereinafter be described.

One of the principal advantages of the construction above described is the provision of the combs 7 and 8 and the partitions 4 in such a manner that they may each be connected to their respective covers 1 and 2 in a single sewing operation. Furthermore, the provision for joining the tabs 5^a—5^a adjacent their center is preferable inasmuch as the covers 1 and 2 may be drawn together or flattened in such a manner as to permit each pair of tabs 5^a—5^a to be folded outwardly and the other unassembled parts folded back, so that said tabs project from the part of the cover already assembled, and may thus be quickly sewn together along the seam 5^b.

A further advantage of the construction described is that the sides of the partitions 5 are loose, that is to say, they are not joined along their side margins to the partition 4, in the preferred form shown, being spaced slightly on opposite sides of each partition 4, thus permitting the flexibility that is essential to rapid and convenient 103 loading of the cushion with resilient material.

The cushion described is particularly adapted for use with resilient springs comprising helical coils of wire, which springs 110 may be inserted through the loose side of each row of compartments. As a preferred method of loading the cushion with springs, an implement known as a loading tool is used in which a number of springs equivalent 115 to the number constituting a single row, are held flatly compressed within the tool. The tool is then inserted into the open end of the cushion and along one side of each longitudinal compartment formed between successive partition strips 4, the tool being held so that the flattened springs pass through the openings between the partition strips and the adjacent edges of the tabs. It will be understood, however, that a cushion cover constructed in accordance with my invention may also be loaded with other resilient cushioning means.

As before explained, the process of assembling the cushion cover from correspond-

ing combs 7 and 8 and transverse partitions 4, results in a marked saving of time, labor and material in the manufacture of the cover, eliminating the sewing of a multitude 5 of short seams, each of which may be a separate sewing operation.

I claim as my invention:

1. A cushion cover construction comprising top and bottom cover pieces, a plurality 10 of parallelly disposed combs each consisting of a single piece of material sewn to said cover pieces along one edge and provided with spaced cuts extending from the free outer edge substantially down to said sewn 15 edge, a plurality of partition strips arranged transversely of said combs and sewn to said cover pieces along lines passing through aligned cut portions of said combs, said combs being slightly more than one-half 20 the height of the completed cushion and sewn together along their abutting edges.
2. A spring cushion container comprising top and bottom pieces of cover material, parallel and oppositely disposed combs sewn 25 along their connecting edges to each of said pieces of cover material and sewn together

at their adjacent registering edges, and partition strips constituting a continuous piece of material substantially twice the height of said combs sewn to each of said cover 30 pieces on lines extending at right angles to said combs and passing through aligned rows of cuts therein.

3. A cushion cover construction comprising top and bottom cover pieces, a plurality 35 of parallelly disposed combs each consisting of a single piece of material sewn to said cover pieces along one edge and provided with spaced cuts extending from the free outer edge substantially down to said sewn 40 edge, a plurality of partition strips arranged transversely of said combs and sewn to said cover pieces along lines passing through aligned cut portions of said combs, each abutting pair of combs having aggregate 45 height slightly more than the height of the completed cushion and being sewn together along their abutting marginal edges.

Signed at Chicago this 13 day of July 1925.

SAMUEL SUEKOFF.
